UNITED STATES PATENT OFFICE

ARTHUR S. HALVERSON, OF FULLERTON, NEBRASKA

SIGNALING DEVICE

Application filed May 26, 1928. Serial No. 280,843.

This invention relates to signal devices adapted to indicate the direction of travel of a vehicle.

Another object of the invention comprehends signal elements included upon the vehicle and adapted to be turned in the proposed direction of travel.

Another object of the invention comprehends an operating mechanism adapted for connection with the signal elements to turn and illuminate the signaling elements when shifted to occupy their respective positions.

A further object of the invention consists of cut-off devices whereby switch members for the operating mechanism may be left in their initial positions and the electrical energy will be shut off when the signal reaches its purported position.

More specifically stated the signal elements are provided with signal faces whereby other vehicles approaching the signal equipped vehicle may readily determine the direction of travel and the proposed direction of travel of the particular vehicle before the detour is executed.

With the above and other objects in view, the invention further consists of the following novel features and details of construction, to be hereinafter more fully described, illustrated in the accompanying drawings and pointed out in the appended claim.

In the drawings:—

Figure 1 is a fragmentary side elevation of a vehicle with the invention applied for use in conjunction therewith.

Figure 2 is a side elevation of one of the signal elements.

Figure 3 is a top plan view of one of the signal elements.

Figure 4 is a sectional view taken through the operating mechanism and disclosing the particular mounting for the signal elements.

Figures 5 and 6 are sectional views taken through the operating mechanism upon the sectional line 5—5 of Figure 4 to disclose the respective relative positions of the operating mechanism for the supporting means of the signal elements.

Figure 7 is a sectional view taken on line

7—7 of Figure 4 and illustrative of a neutral position for the operating mechanism.

Figure 8 is a top plan view of a portion of the control mechanism.

Figure 9 is a sectional view taken on line 9—9 of Figure 2.

Figure 10 is a horizontal sectional view taken on line 10—10 of Figure 2.

Figure 11 is an end elevation of one of the signal elements.

Figure 12 is a transverse sectional view taken on line 12—12 of Figure 2.

Figure 13 is a diagrammatic view of the wiring circuits.

Referring to the drawings in detail, wherein like characters of reference denote corresponding parts, the reference character 10 indicates a vehicle having supports 11 adapted to accommodate housing members 12 for an operating mechanism, the construction and operation of which will be presently described.

The housings 12 are subdivided into compartments 13, 14 and 15 by partitions 16, 17 and 18 respectively, substantially as illustrated in Figure 4 of the drawings.

Tubular members 19, extended within the tops of the housings 12, are also disposed within registering openings in the respective partitions. The lowermost ends of the tubular members 19 are provided with collars 20 having circumferential grooves 21 adapted to accommodate the innermost peripheral edges of apertured disks 22 carried upon the lowermost compartments 18 to journal the tubular members and sustain the same in elevated positions.

Signal elements, such as indicated at 23, constructed after the manner of arrows, are hollow throughout their lengths; the side walls of the reduced portions thereof and the pointed ends are cut away and replaced by transparent panels 24.

The inner or feather ends of the arrows are also faced upon the sides thereof by panels 25 colored to designate the characteristics of feather guides upon the innermost ends of arrows. An enlarged portion or lamp compartment 26 being provided between the reduced portion of the arrow and

feather end thereof. A lamp 27, positioned within the compartment 26, is wired to the tubular member 19. The forward walls 28 are formed of amber or yellow colored panels, whereby approaching traffic will be informed as to the direction of travel pursued by the particular vehicle and any purported detour before the latter is executed. Said lamp will illuminate the transparent panels 24 and 25 and the enlarged portion 26. The forward end walls 28 are in the nature of colored panels adapted to indicate that the arrow is pointing toward an approaching vehicle, whereas the rear panel 29 is red to indicate the back of the arrow and which under ordinary driving conditions may be employed as a tail light.

The operating mechanism comprehends a pair of solenoid coils A and B carried upon the partition 18, a solenoid C upon the partition 17 and a solenoid D upon the partition 16. The solenoids A and B are disposed in the positions shown in Figure 5 of the drawings to selectively energize the contact portions 30 and 31 of complementary arms 32 and 33 respectively. Cross arms 34, laterally disposed upon the tubular members 19, are adapted for pivotal connection at their outermost ends with arcuate-shaped arms 35 adapted for connection with the adjacent ends of the complementary arms 32 and 33. The neutral position of the signal element is illustrated by the operating mechanism in Figure 6 of the drawings.

As mentioned in the foregoing, I have provided a control mechanism adapted for use in conjunction with the operating mechanism to cut-off the electrical energy to and from the signal elements and operating mechanism therefor and in carrying out the invention, I have provided a plate member 36 of disk like formation and which is fixedly connected with a tubular member 19 for simultaneous rotation therewith. A spring locking dog 37, located adjacent the working end of the solenoid D, is adapted for selective reception within cut-out portions 38 in the outer curved edge of the plate member 36. The cut-out portions 38, as illustrated in Figure 8 of the drawings, are preferably three in number. A cam 39, carried upon the undersurface of the plate member 36, is adapted to selectively engage spring contact fingers 40, 41 and 42 adapted for contacting engagement with contact members 43, 44 and 45 respectively for automatically breaking the circuit when the arrow occupies its predetermined positions.

From the diagrammatic view in Figure 13 of the drawings, it is noted that the master switch 46 when swung to the left for contacting engagement with the contact 48 that the current will flow from the source of current 47 through the master switch 46,

the contact 48, the conducting wire 49, the spring contact finger 42, the contact member 45 and the corresponding wire leading therefrom to the solenoid A; the latter being connected in series with the solenoid D, whereby the aforementioned action of the master switch 46 will flash the lamp bulb 27 within the arrow after the same passes over the series of contacts 55. When the master switch 46 is disposed in the left position, the solenoids A and D respectively will be simultaneously energized to rotate the plate member 36 and release the locking dog 37 from the particular cut-out portion 38, whereby the arrow will be swung to occupy a left position. Upon arriving at such position, the cam 39 carried upon the undersurface of the plate member 36 will engage the contact finger 42 and break the circuit between the source of current 47 and the solenoids A and D, whereby the arrow or signal will remain in the aforementioned position, the lamp 27 will remain illuminated but the solenoids A and D will be deenergized.

In like manner, the master switch 46 when swung to occupy a right position, that is to the right of the contact 52 for contacting engagement with the contact 50, the current will then flow from the source of current 47 through the switch to the contact 50 through the conducting wire 51 to the contact member 44, the spring finger 41 and the adjacent conducting wire to the solenoid B, which is in turn connected in series with the solenoid D. The operation of the right-turn signal is likened to that of the left-turn signal in operation.

The master switch 46 when swung from either a right or left turn position and contacting the contact 52 will cause the current to flow from the battery or other source of current, as indicated at 47, to pass through the conducting wire 53 through the contact finger 40 and the contact member 43, which is in turn connected with a solenoid C. The solenoid C being connected in series with the solenoid D, whereby the locking dog 37 will be released from the adjacent cut-out portion 38 in the plate member 36 and the arrow of the signal element will then be shifted to occupy a normally inactive position, namely, pointing straight ahead or in parallelism with that of the vehicle.

It is to be noted that lateral shifting movement of the master switch 46 for contacting engagement with the contacts 48, 50 and 52 respectively will also selectively engage the multiplicity of contacts 55 disposed in the path of movement of the master switch 46, whereby the lamp bulb 27 within the arrow or signal element will be successively flashed, whereby the proposed detour or direction of travel of the particular ve-

hicle will be readily ascertained by other motorists advancing the particular vehicle in either direction, inasmuch as the flashing of the lamp bulb within the signal element 5 or arrow will put the approaching motorists on guard.

From the illustration in Figure 13 of the drawings, it will be noted that the particular location of the master switch 46 and the 10 contact member 41 will be depressed to break the circuit between the conducting wire 53 and the contact member 43, whereby the solenoid C will be deenergized by the signal element to occupy a neutral position and 15 the lamp bulb 27 will still burn, and the rear panel 29 in the signal element, being red, may be effectively employed as a tail or parking lamp.

As illustrated in Figure 13, the lamp bulb 27 for the signal arrow, is provided with a conducting wire 54 and which in this instance is adapted for connection with a series of contacts 55 located in juxtaposition to the contacts 48, 50 and 52 respectively, 25 whereby the master switch 46, when swung to occupy its respective positions, will simultaneously close both circuits, whereby the signal element may be illuminated when swung to occupy signal positions.

In Figure 7 of the drawings, the solenoid C is disclosed and which is adapted to return the signal element to its neutral position, after being initially shifted to either the right or left. Contact portions 56, carried upon companion arms 57, pivotally mounted as indicated at 58, are adapted to be simultaneously energized to swing across arm 59 having connection with the adjacent ends of the arms 57 through the instrumentality of links 60.

From the foregoing, it is to be noted that the particular signal may be shifted to occupy signal positions, precedent to making a detour, whereby motorists approaching the 45 particular equipped vehicle will be well informed as to the proposed direction of travel of the vehicle, long before the turn is made and in both day and night, inasmuch as the signals may be illuminated and 50 the walls 28 and 29 of the signal elements will readily indicate, at night, the direction of travel of the vehicle.

The invention is susceptible of various changes in its form, proportions and minor 55 details of construction, and the right is herein reserved to make such changes as properly fall within the scope of the appended claim.

Having thus described the invention, what 60 is claimed is:—

In a direction signal, a housing, a signal carrying shaft mounted therein, means to normally lock the shaft against rotation comprising a member mounted on said shaft 65 and a movable locking member cooperating

therewith, electrically controlled means to actuate the movable locking member and release the shaft, electrically operated means to rotate the shaft to active signaling position, means to simultaneously close a circuit through the electrically controlled means and the shaft rotating means, means to interrupt the circuit to the electrically controlled means to permit the movable member to return to normal locking position, 70 electrically operated means to return the shaft to inactive position, and means to simultaneously close a circuit through the electrically controlled means and shaft returning means to restore the parts to normal 75 position.

In testimony whereof I affix my signature.
ARTHUR S. HALVERSON.
